UNITED STATES PATENT OFFICE

2,557,366

POCKET CONSTRUCTION

Carl H. Wennerstrom, Chicago, Ill.

Application October 29, 1949, Serial No. 124,373

1 Claim. (Cl. 2—254)

1
The invention relates to pockets for men's trousers and more particularly to a safety pocket for preventing the loss of currency, coins, or other objects carried therein.

Currency and other objects are frequently lost from conventional trouser pockets when the wearer of the trousers is reclining or sitting in an inclined position. Attempts have been made to construct pockets having means for catching coins or other objects that otherwise would be lost, but such pockets either are so restricted as to prevent entrance of the full hand to the bottom of the pocket, or else are characterized by other undesirable features, such as sub-pockets of limited capacity that make the pocket unduly expensive.

One of the objects of this invention is to provide a safety pocket having a capacious sub-pocket formed integrally therein.

Another object of this invention is to provide a safety pocket having a guard extending across the pocket chamber which does not prevent the entrance of the full hand to the bottom of the pocket.

A further object of this invention is to provide a safety pocket having a guard extending across the pocket chamber, which guard also serves as a wall of a sub-pocket formed in said safety pocket.

A still further object of this invention is to produce a safety pocket that is simply constructed, economically manufactured, and is efficient in use.

Further objects and advantages of this invention will become apparent as the following description proceeds and the features of novelty which characterize this invention will be pointed out with particularity in the claim annexed to and forming part of this specification.

A preferred embodiment of the invention is shown in the accompanying drawing, in which:

Figure 1 is a side view of a pair of trousers showing the location of the improved pocket in the trousers;

Figure 2 is a side view of the improved pocket;

Figure 3 is a view of the pocket blank;

Figure 4 is a cross-sectional view of the edge stitching of the pocket blank taken on the line 4—4 of Figure 3;

Figure 5 is a cross-sectional view of the inside folded edge of the pocket taken on the line 5—5 of Figure 2; and

Figure 6 is a cross-sectional view of the closed edge of the pocket taken on the line 6—6 of Figure 3.

2
Referring to Figure 1 of the drawing there is shown a pair of trousers 10 equipped with the novel pocket construction. The location of the improved pocket 11 in the trousers 10 is shown in dotted lines. The pocket mouth is designated by numeral 12.

Referring next to Figure 2, the pocket 11 is shown as having an inside folded edge 13 which extends from the top to the bottom of the pocket. 10 A top edge 14 is shown at right angles to the inside folded edge 13. A pair of mouth edges 15 and 16 extend downwardly from the ends of the top edge 14. The ends of the top edge 14 intersect the top ends of the mouth edges 15 and 16 at corners 17. The lower ends of the mouth edges 15 and 16 are joined together at corner 18. These mouth edges 15 and 16 also slope relative to the inside folded edge 13 so that the distance between the corners 17 and the inside folded edge 13 is less than the distance between the corner 18 and the inside folded edge 13.

The pocket 11 further has a closed edge 19 which meets the lower ends of the mouth edges 15 and 16 at corner 18. This closed edge 19 has 25 a portion 20 which begins at the corner 18 of the pocket 11 and extends downwardly. Closed edge portion 20 also extends outwardly relative to a downward projection of the straight mouth edges 15 and 16. This outward path of the closed edge 19 bulges relative to a downward projection of the mouth edges 15 and 16 creates an enlargement in the pocket 11 which serves as a sub-pocket 24. It will be noted that the distance between the closed edge portion 20 and the inside 30 folded edge 13 is constantly increasing as one progresses downwardly from corner 18 along the upper part of the edge 19. The remaining portion of the closed edge 19 is curved downwardly and inwardly toward the inside folded edge 13 and continues until the closed edge 19 joins the inside folded edge 13 at corner 21a.

A line of stitching 22 extends inwardly into the pocket 11 from the corner 18 toward the corner 21a, as indicated by a dot-dash line in Figure 2. 45 The inner end 23 of the line of stitching 22 preferably extends no closer to the inside folded edge 13 than the distance between corners 17 and the inside folded edge 13.

The mouth edges of a pocket are usually parallel to the inside folded edge of the pocket. By limiting the distance that the line of stitching 22 extends into the pocket 11, an open portion between the inner end 23 of the line of stitching 22 and the inside folded edge 13 is provided which 55 preferably is at least as great as the distance be-

3

tween the corners 17 of the mouth edges and the inner folded edge 13 of the pocket 11. This spacing of the inner end 23 of the line of stitching 22 from the inside folded edge 13 provides a passage to the bottom of the pocket 11 which preferably is at least as great as the passage through a full rectangular pocket having a cross-section equal to the cross-section of the pocket 11 at its top edge.

The line of stitching 22 further cooperates with an opposed portion of the closed edge 19 to form therebetween the sub-pocket generally designated by the numeral 24. When the pocket 11 is tilted so that the mouth edges 15 and 16 of the pocket are facing downwardly, the line of stitching 22 and the opposed portion of the closed edge 19 forms upright sides of the sub-pocket 24. At the same time, the portion of the closed edge 19 designated by the numeral 20 serves as the bottom edge of the sub-pocket 24. Since the pocket 11 as shown in Figure 2 is inclined by rotating the pocket in a clockwise manner, the line of stitching 22 also serves to direct the contents of the pocket 11 into the sub-pocket 24 whereby the contents are prevented from escaping through the mouth of the pocket 11.

Referring to Figure 3, the pocket blank is shown as being symmetrical about a vertical axis 25. The edges of the blank are the straight top edge 14, a pair of sloping side edges 15 and 16, and a curved lower region edge generally designated by numeral 26. The curved lower region edge comprises a pair of upper portions 27 and a pair of lower portions 28. The upper portions 27 begin at the lower end of the side edges and extend downwardly. The upper portions 27 also extend outwardly relative to a downward projection of the sloping side edges 15 and 16 so that the distance between the upper portion 27 and the vertical axis 25 increases as one moves downwardly along the run of said upper portion 27. The lower portions 28 begin at the furthermost extended point of the upper portions 27. These lower portions 28 extend downwardly and inwardly toward the vertical axis 25 until they join each other at the vertical axis 25.

To form the pocket 11, the blank is folded about the axis 25 and the upper portions 27 and the lower portions 28 of the curved lower region edge 26 of the pocket blank are stitched together to form the closed edge 19 of the pocket 11. The axis 25 of the blank coincides with the inside folded edge 13 of the pocket 11.

Figure 4 is an enlarged view of the stitching at the edge of the blank shown in Figure 3. One set of stitches extends from the edge of the blank

inwardly and is designated by the numeral 29. The other set of stitches extends across the inside ends of the first set of stitches 29 and is designated by the numeral 30. This stitching 30 prevents any unraveling of the material which forms the pocket. Figure 6 shows the way two stitched edges of the type shown in Figure 4 are joined together to form the closed edge 19 of the pocket 11.

10 While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new and desire to secure by Letters Patent of the United States is:

20 A one-piece side pocket for men's trousers comprising a pair of opposed single thickness walls connected along a straight inside folded pocket edge, said opposed walls being formed with top edges, lateral substantially coincident mouth edges and a closed edge, said top edges, mouth edges and closed edge being joined, respectively, at the upper and lower corners of the mouth of said pocket, said mouth edges sloping rearwardly and said closed edge including an upper outwardly bulging portion and a lower downwardly sloping portion forming the bottom of said pocket, said walls being stitched together along a line extending from the lower corner of said mouth toward the lower end of said folded edge and terminating at a point spaced from said folded edge by substantially the same distance as the upper corner of said mouth, said line of stitching and said bulging portion of the closed edge defining a sub-pocket freely accessible to the hand and capable of catching pocket contents when said contents would otherwise gravitate out through the mouth of said pocket.
